UNITED STATES PATENT OFFICE.

EDWARD ERNEST WARD, OF CHICAGO, ILLINOIS.

FUEL-SAVING DEVICE.

1,352,043.

Specification of Letters Patent.

Patented Sept. 7, 1920.

Application filed April 29, 1918, Serial No. 231,500. Renewed July 20, 1920. Serial No. 397,753.

To all whom it may concern:

Be it known that I, EDWARD E. WARD, a citizen of the United States, residing at Chicago, in the county of Cook and State 5 of Illinois, have invented a new and useful Fuel-Saving Device, of which the following is a specification.

The subject of the present invention is a fuel saving device, and the main object of 10 the invention is the provision of means for heating the air which is to be introduced into the firebox of a furnace by the ordinary and well known blast means.

The blast means, while utilized for introducing or injecting any fine or pulverized fuel into a furnace, finds its principal use 15 in conjunction with wood working plants, where it is utilized for removing sawdust, shavings and the like from the plant and introducing them to the firebox of the furnace 20 of the plant. A large quantity of cold air is necessarily carried to the firebox with the shavings and the like, and the introduction of this cold air necessitates the consumption 25 of a large amount of fuel. It is to overcome this to some extent that the present invention has been devised.

Another object of the invention is the provision of means for thoroughly mixing hot 30 air with the air in the blast pipe.

A still further object of the invention is the provision of means for drawing hot air from the furnace.

The invention also contemplates generally 35 improving the construction and enhancing the utility of fuel saving devices of this character.

With the foregoing and other objects in 40 view which will appear as the description proceeds, the invention resides in the combination and arrangement of parts and in the details of construction hereinafter more fully described and claimed, it being understood that changes in the precise embodiment 45 of the invention herein disclosed can be made within the scope of what is claimed without departing from the spirit of the invention.

A practical embodiment of the invention 50 is shown in the accompanying drawing, wherein:—

Figure 1 is a perspective view of the invention showing the same in place upon a furnace, a fragmentary portion of which is 55 shown;

Fig. 2 is a view in elevation, partly in section, of a fragment of the device, showing the connection between the blast pipe and the hot air pipe;

Fig. 3 is a sectional view of the same taken 60 at right angles to the plane of Fig. 2.

An ordinary furnace is indicated at 1 and into the firebox of the furnace is led the blast pipe 2.

In carrying out the invention, a branch 65 pipe 3 is secured to the pipe 2 which pipe 3 is preferably provided with a damper 4 for the purpose of closing the pipe 3 when the device is not in use. At the junction of the pipe 3 with the pipe 2, and within the pipes, 70 is mounted a beater or mixing wheel 5, against the vanes of which air passing through the pipe 3 to the pipe 2 is deflected by a deflector plate 6 which is secured to the wall of the pipe 3.

The pipe 3 is connected with the outlet 75 of a fan casing 7 in which turns a fan 8 which is rigid on a shaft 9. The shaft 9 has a pulley 9' rigidly secured thereon for the purpose of belting the shaft to a suitable 80 source of power for driving the fan. The intake pipe 10 of the fan casing 7 leads into any suitable part of the furnace 1 from which products of combustion and hot air may be drawn, and terminates in a hood 11. 85

While the pipe 10 may extend into the flue-cap chamber, or any other available part of the furnace from which hot air may be drawn, it is herein shown as extending into the flue-cap chamber 12 of the furnace 1. 90

The blast drives by means of a blast of air, shavings and other fuel into the firebox of the furnace through the pipe 2. At the same time the fan 8 is rotated, drawing hot air from the flue-cap chamber 12 and expelling it through the pipe 3 into the pipe 2. As the air passes through the pipe 3 it strikes the baffle plate 6 and is deflected against the vanes of the beater wheel 5. This will cause a rotation of the beater 100 wheel, which rotation will tend to mix the hot air thoroughly with the cold air of the pipe 2. 95

From the foregoing it will be apparent that the hot air is withdrawn from a place 105 from which it would have gone to waste up the chimney and, consequently, has caused no loss in furnace efficiency. It will also be evident that the air introduced into the furnace through the pipe 2 will be considerably 110

warmed and will not cause the consumption of so much fuel in keeping up the furnace heat.

Having thus described the invention, what is claimed as new and sought by Letters Patent, is:—

In combination with a furnace, and cold air intake pipe thereof, a flue cap chamber, a hood positioned within the flue cap chamber of the furnace, a casing outside of the furnace, a pipe providing communication between the hood and casing, a rotary fan within the casing, a relatively short pipe providing communication between the casing and cold air pipe, said short pipe having an enlarged end portion, a mixing fan

mounted in the enlarged portion, the blades thereof extending into the cold air pipe, a curved deflector plate secured to the inner wall of the relatively short pipe, the lower end of the deflector plate terminating at a point adjacent the path of travel of the mixing fan, for directing a blast of air onto the blades thereof.

In testimony that I claim the foregoing as my own, I have hereto affixed my signature in the presence of two witnesses.

EDWARD ERNEST WARD.
